(57) **CLAIM**

The ornamental design for a semi-truck front windshield, as shown and described.

DESCRIPTION

FIG. 1 is a top perspective view of a semi-truck front windshield;

FIG. 2 is a front side elevational view of the semi-truck front windshield shown in FIG. 1;

FIG. 3 is a left side elevational view thereof;

FIG. 4 is a right side elevational view thereof; and,

FIG. 5 is a top plan view thereof.

The broken lines in the drawings illustrate portions of the semi-truck front windshield which form no part of the claimed design.
